UNITED STATES PATENT OFFICE

154,975

DESIGN FOR A TIE HOLDER

Carl A. Anderson, Cranston, R. I., assignor to
Anderson Tool & Die Works, Inc., a corporation
of Rhode Island

Application January 13, 1948, Serial No. 143,694

Term of patent 3½ years

(Cl. D17—10)

To all whom it may concern:

Be it known that I, Carl A. Anderson, a citizen
of the United States, residing at Cranston, in the
county of Providence and State of Rhode Island,
have invented a new, original, and ornamental
Design for a Tie Holder, of which the following
is a specification, reference being had to the ac-
companying drawing forming a part thereof.

Fig. 1 is a front elevation of a tie holder, show-
ing my new design; and

Fig. 2 is a side view thereof.

I claim:

The ornamental design for a tie holder, sub-
stantially as shown.

CARL A. ANDERSON.
